ACCORDION CARRYING CASE

Maxwell Meyers, New York, N. Y.

Application December 24, 1937, Serial No. 181,528

8 Claims. (Cl. 206—13)

This invention relates to accordion carrying cases.

Heretofore, accordion cases have been constructed in such manner that they were cumbersome and unwieldy. In order to remove accordions from cases as heretofore made, one had to literally exert much effort as some cases would tip or rock from side to side, others would require one to forcefully pick up the accordion by the straps and pull it out of the case, thus requiring the full weight to be borne by the user and also unduly straining the accordion structure.

In addition to the foregoing disadvantages these cases were grotesque in appearance and did not distribute the weight of the accordion evenly causing much annoyance and inconvenience to the carrier.

It is a general object of this invention to provide a simple, efficient, economical and practical accordion case constructed to overcome the aforesaid disadvantages.

A further object of the present invention is to provide an accordion case which will facilitate the removal of and the placement therein of a piano accordion.

Another object contemplated is to provide an accordion case which distributes the weight of the accordion evenly in order to facilitate the carrying thereof.

Another object contemplated is to provide an accordion case with a bottom so constructed as to permit the ready and easy withdrawal of the accordion.

It is a further object to provide an accordion case with a base so constructed as to provide a compartment to store various articles used in connection with an accordion.

Other objects and advantages will be apparent from the following description in which:

Fig. 1 is a perspective view of an opened accordion case embodying the invention.

Fig. 2 is a transverse sectional view of an accordion case in open position.

Fig. 3 is an end view of an accordion carrying case in its closed position.

Fig. 4 is a fragmentary detail sectional view of the cover and the compartment.

The invention in one of its embodiments is exemplified in a case comprising a cover 25 and a body 26, pivotally connected as at 27. The side wall 30 of the body 26 is bellied as indicated at 28, intermediate the oppositely sloping portions 28' and 28''.

The cushioning inner means 29 is secured in any suitable manner to the side wall 30 of the body 26 and prevents the accordion "A", and particularly the bass shift mechanism thereof from contacting said side wall.

The body portion 26 is provided with a bot-

tom 34 which preferably slopes downwardly from the open front of the body 26 to its rear side wall 30. By so sloping the base 34 the instrument is kept within the body even though cover 25 (later described) is open.

This inclined bottom 34 forms with the base 50 a pocket or compartment 35 for storing articles usually used in connection with the instrument and is hinged in any suitable manner as indicated at 34' so that it may be lifted by means of the tab 36 to gain access to the compartment 35. The swingable bottom 34 is supported by the side blocks 37 which rest on the base 50. Base 50 has an upwardly directed extension 50' to which is hingedly attached at 27 the cover 25. This extension 50' is provided with a recess 51 to facilitate the closing of the cover 25.

It is to be particularly noted that the bottom 34 slopes upwardly in the direction of opening O through which the instrument is placed within and withdrawn from the body 26.

This not only facilitates the retention of the accordion within the body 26 as hereinabove stated but also facilitates removal of the accordion because the incline is in the direction of the path or line of removal of the accordion.

The body 26 is preferably made in three layers, an outer layer 32 of any suitable covering material such as fabrikoid, imitation leather, an inner of any suitable dress material 33, such as plush or velvet and an intermediate layer 31 of suitable rigid substance, such as, wood or fiber board.

The cover may likewise be made of similar material 32', 33', 31', respectively.

The cover 25 is provided with side blocks 42, 43 to keep the accordion from shifting.

Body 26 carries at its top 38 the conventional handle 39 and the lock straps 40. Metal knobs 41 on body 26 and cover 25 assist in preventing abrasion of the same. Cover 25 may be provided with a bevel edge 25' which is accommodated within recess 44 of body 26, when the cover is closed. The lock portions 45, 45' are secured to the upper portion 46 of the cover 26. Hinge 27 is secured by means of screws 47.

Referring to Figure 2, the center line of gravity is indicated at 48.

It is thus apparent that an accordion case constructed according to my invention distributes the weight evenly thus providing a perfectly balanced, attractive, and extremely practical accordion case, which may be easily carried.

It is to be observed that the case is so designed that the back B of the accordion is at all times adjacent the cover 25 so that if the case is in an upright position and the cover opened the accordion will remain in an upright position while the cover is being opened and its removal facilitated by its withdrawal along 60

the inclined plane 34; or the case may be positioned with its cover 25 at the bottom, which when the body 26 is swung upward relatively thereto, forms a base for the support of the accordion, the latter being substantially free and uncovered and thus easily handled.

It is to be further noted that the base of the case which supports the accordion in an upright position is part of the body 26 and that the accordion is substantially and entirely disposed within the body 26 when placed therein.

In Fig. 2 the dotted lines indicate the position of the accordion when the case is resting in an upright position.

15 It is further to be observed that an accordion case made in accordance with my invention permits the accordion straps S to remain positioned next to the back of the accordion even when the case is closed.

20 This obviates the heretofore disadvantage inherent in prior art accordions carrying cases of the necessity of placing the carrying straps S upon the grill and causing pressure on this delicate portion of an accordion when put in a carrying case.

25 From the foregoing it is apparent that a practical and attractive accordion carrying case is exemplified.

30 Although the drawings, and the above specification disclose the best mode in which I have contemplated embodying my invention, I desire in no way to be limited to the details of such disclosure, for in the further practical application 35 of my invention many changes in the forms and proportions may be made as circumstances require or experience suggests without departing from the spirit of the invention within the scope of the appended claims.

30 Having thus described my invention what I claim as new and desire to secure by Letters Patent, is:

1. An accordion case comprising a body having a substantially straight bottom, a back, an open front, a cover hingedly attached to said body substantially near said bottom, members near the ends of said bottom sloping downwardly from said open front towards said back providing with said bottom a compartment, and a floor over said compartment constituting both a cover for said compartment and a base upon which an accordion may be supported.

2. An accordion case for holding an accordion in substantially balanced vertical position comprising a body having a substantially straight bottom, a back and an open front, said body having a floor sloping downwardly from said open front to said back providing a base upon which an accordion may be supported on its base end with its back towards said open front, the angularity of said floor being such as to dispose the accordion within said body in said position on its base end and to facilitate the removal of the accordion from said body.

3. An accordion case comprising a body having a substantially flat bottom, a back, and an open front, said back sloping in opposite directions from a line intermediate the top and bottom thereof toward said open front, and a floor sloping downwardly from said open front towards said back, the angularity of said floor being such

as to support the accordion substantially within said body on end in substantially balanced vertical position.

4. An accordion case comprising a body having a substantially flat bottom, a back, and an open front, said back sloping in opposite directions from a point intermediate the top and bottom thereof toward said open front, a floor sloping downwardly from said open front towards said back providing a base upon which an accordion may be supported in said body, the angularity of said floor being such as to dispose the accordion within said body in a substantially vertical position, a cover for said open front, and means in said case adapted to press against the accordion when placed in said body for retaining the same in place and against shifting.

5. An accordion case comprising a body having a substantially straight bottom, a back and an open front, said body having a floor sloping downwardly from said open front to said back, the angularity of said floor being such as to provide a base upon which an accordion may be supported in substantially vertical position within said body and which facilitates the removal of an accordion from said body.

6. An accordion case for holding an accordion in substantially balanced position comprising a body having a substantially straight bottom, a back and an open front, said body having a floor sloping downwardly from said open front to said back providing a base upon which an accordion may be supported on its base end with its back towards said open front, the angularity of said floor being such as to dispose the upper back edge of the keyboard portion of the accordion in substantially the same vertical plane with the back edge of the base end when placed in the case.

7. An accordion case for holding an accordion in substantially balanced position comprising a body having a substantially straight bottom, a back and an open front, said body having a floor sloping downwardly from said open front to said back providing a base upon which an accordion may be supported on its base end with its back towards said open front, the angularity of said floor being such as to dispose the upper back edge of the keyboard portion of the accordion in substantially the same vertical plane with the back edge of the base end when placed in the case, said back sloping from said bottom to conform to the general shape of the front portion of the accordion.

8. An accordion case for holding an accordion in substantially balanced position comprising a body having a substantially straight bottom, a back and an open front, said body having a floor sloping downwardly from said open front to said back providing a base upon which an accordion may be supported on its base end with its back towards said open front, the angularity of said floor being such as to dispose the upper back edge of the keyboard portion of the accordion in substantially the same vertical plane with the back edge of the base end when placed in the case, and cushioning means at said back of the body for firmly retaining said accordion in position.

MAXWELL MEYERS.
